UNITED STATES PATENT OFFICE.

HERMAN NORECK, OF NORFOLK, VIRGINIA.

BROILER.

1,010,169.

Specification of Letters Patent. Patented Nov. 28, 1911.

Application filed June 13, 1911. Serial No. 632,945.

To all whom it may concern:

Be it known that I, HERMAN NORECK, a citizen of the United States, and a resident of Norfolk, in the county of Norfolk, State 5 of Virginia, have invented a certain new and useful Broiler, of which the following is a description.

My invention relates to improvements in broilers in which the flame is directed at the same time from above and below toward 10 the food to be broiled, and in which the grate and the lower bank of jets may be readily raised toward or lowered from the upper bank of gas jets; and the objects of 15 my improvement are—

To provide a broiler using gas fuel, broiling from above and below at one and the same time, without turning the meat to be broiled, and in addition to these advantages 20 attained by my earlier invention, embodied in a prior application, filed March 21, 1911, Serial No. 615,963, admits of adjusting the broiler easily and quickly to all sizes and thicknesses of meat to be broiled, without 25 removing or handling the hot grate, and without stopping or interfering with the operation of broiling.

Other objects will appear from the hereinafter description.

I attain these objects by the mechanism 30 illustrated in the accompanying drawings, in which—

Figure 1 is a front view of my improved broiler; Fig. 2 is a side view; Fig. 3 is a 35 plan view of the lower perforated burner pipes, the frame on which they are carried, and the adjacent pipe connections, and Fig. 4 is a sectional view.

Similar letters refer to similar parts in 40 the several views.

A is the body of my improved broiler, comprising an outer case, a warming oven flue, and standards for upholding the whole.

45 B is one of the upper perforated burner pipes, and B' is one of the lower perforated burner pipes.

C and C' are burner cocks; D is a drip trough; D' is a lower drip trough, and d 50 is an outlet pipe therefrom for conducting grease to a receptacle not shown.

E is the inlet gas supply pipe connected directly with the upper burner pipes B and 55 through the flexible metallic pipe F with the lower bank of burner pipes, B'.

E' is the lower gas supply pipe for the lower bank of burners.

F is a flexible metallic gas pipe coil connecting the upper gas supply pipe E with the lower gas supply pipe E'.

G is the upper member of the grate, consisting of a plurality of grate bars, g, each convex upward and each separated from its adjacent bar by a narrow longitudinal space, g'.

H is the lower member of the grate, comprising a plurality of grate bars, h, concave upward, each separated from the adjacent grate bar by a narrow longitudinal space, h'.

I is the frame carrying the grate G—H, and the gas supply pipe E' and the lower perforated burner pipes B', which may be raised and lowered in the guides I' by the upright support K, having a lower threaded portion turning in the nut L, which is also a bevel toothed gear wheel meshing with the companion bevel toothed gear wheel L' on the shaft M, operated by the crank N. The nut and bevel gear L has 80 integral with it a collar resting upon the plate O, within which the upright support K is raised and lowered.

P and P' are grooves in the sides of the frame I carrying the grate G—H, giving a 85 plurality of adjustments of the grate G—H to the lower bank of burner pipes as may be required for the length of flame used.

The doors, pipe connections and stop-cocks do not require special mention here, 90 as their uses are all apparent from the drawings.

The operation of my improved broiler is as follows: The grate and the lower bank of gas burners being adjusted in the frame, and being in fixed position with relation to each other, may be lowered or raised. I have an adjustable broiling space between the top bank of burners B and the grate, which may be altered to accommodate the thickness of any meat or other food to be broiled. I may place a steak upon the grate G—H, turning the crank N to raise the broiler to within four inches of the top bank of burners B, then turning on the gas and lighting the flames, the broiling proceeds from below and from above, without turning the steak when broiled. I may broil a thick piece of roast beef by simply lowering the frame I with the grate and lower bank 100 105 110

of burners, by turning the crank N the other way, and I am enabled to make these adjustments by having the flexible metallic gas pipe coil F.

5 Changes and variations of form may be made without departing from the spirit of my invention, for I accomplish in my improved broiler rapid and efficient broiling from above and below without turning the meat; and I may effect all the nice adjustments of the gas flames to the meat, whatever the thickness of the meat may be, without the annoying hand-work of withdrawing the hot grate from a slide and adjusting it in another slide.

10 15 Having now described my invention, what I claim as new and desire to secure by Letters Patent is—

1. In a broiler, an oven containing a grate, 20 and gas jets, a grate, means for supplying gas to the gas jets, a lower bank of gas jets adapted to project the flames upward, means for raising and lowering the grate and lower bank of gas jets together, without removing the same from the oven, an upper bank of 25 gas jets adapted to project the flames downward toward the grate, means for connecting the gas supply of the upper bank of

gas jets with the lower bank of gas jets in various relative positions.

2. In a broiler, an oven containing a grate and gas jets, a double grate, the lower member of which comprises grooved grate bars concaved upward in combination with an upper grate member, whose bars in cross section are convex upward, each arranged over one of the spaces between the bars of the lower grate, a lower bank of gas jets adapted to project the flames upward, means for raising and lowering the grate and lower bank of gas jets together without removing the same from the oven, an upper bank of gas jets adapted to project the flames downward, means for supplying gas to both banks of gas jets, and means for connecting the movable bank of gas jets in its various relative positions with the gas supply.

30 35 40 45 In witness whereof, I have hereunto set my hand at the city, county and State of New York, this 5th day of June, 1911.

HERMAN NORECK.

In presence of—

PHILIP NORECK,
JOHN J. RANAGAN.
